UNITED STATES PATENT OFFICE.

FREDERICK D. MERCER, OF TORONTO JUNCTION, ONTARIO, CANADA.

TENSION-REGULATING MEANS FOR BELTS.

No. 855,899.

Specification of Letters Patent.

Patented June 4, 1907.

Application filed December 14, 1904. Renewed May 2, 1907. Serial No. 371,611.

To all whom it may concern:

Be it known that I, FREDERICK DUNCAN MERCER, of Toronto Junction, in the county of York and Province of Ontario, Canada, have invented certain new and useful Improvements in Tension-Regulating Means for Belts; and I hereby declare that the following is a full, clear, and exact description of the same.

This invention relates to a tension regulating means, for a belt, apron or like device, which will automatically operate to maintain the belt or apron at a substantially uniform tension; and it consists essentially of the combinations and arrangements herein-after described and specifically pointed out in the appended claims.

It has been demonstrated in the field of actual operation that the tension of all classes of belts varies to a greater or less degree, and that these variations of tension are most apparent on those belts or aprons quickly responsive to changes of atmospheric conditions and it is necessary therefore to provide such belts or aprons with tension regulating means which will automatically respond to the contraction and expansion of the material, and by so doing maintain them at substantially uniform tension so that there will be no noticeable variation of the load on the motive power.

For a full understanding of the invention reference is to be had to the following description and to the accompanying drawings in which—

Figure 1—is a perspective view of a belt and the tension regulating means. Fig. 2—is a perspective view of a portion of a belt showing the tension regulating means and a means whereby the connecting members can be lengthened or shortened. Fig. 2^a is a sectional view showing how the tension regulating means is attached to a continuous belt. Fig. 3—is a perspective view on a larger scale than in the preceding views of a means by which connecting members can be lengthened or shortened. Fig. 4—is a plan view of a belt showing the spring of the tension regulating means in section. Fig. 5—is a perspective view of a portion of a belt and the tension regulating means on a larger scale than in the preceding views. Fig. 6—is a sectional view of the construction shown in Fig. 3. Fig. 7—is a perspective view of the binder for locking the connecting member in its adjusted position. Fig. 8 is a perspective

view of an equivalent for the spring shown in the preceding views. Fig. 9 is a perspective view of a narrow belt showing the use of the binders illustrated in Figs. 3 and 6, and Fig. 10 is a perspective view showing the connecting members arranged obliquely to the length of the belt.

Like letters of reference refer to like parts throughout the specifications and drawings.

Hereafter in the specification and claims the term "belt" shall be construed to include in its meaning "belts, aprons, and the like."

In Fig. 1 of the drawings, the ends of the belt *a* are shown to be separated by an intervening space and tied together by the tension regulating means. This tension regulating means consists of a set of guide elements *d*, *d'*, *d''* and *d³* arranged transversely to the length of the belt and located contiguous to one of the ends thereof. Between the intermediate guide elements *d'* and *d''* is the tension regulator *h*, disposed transversely to the length of the belt and which may consist either of an extensible and contractile spring as shown in Figs. 1, 2, 2^a, 4 and 5 or other equivalent means such as an elastic cord, as shown in Fig. 8. In the present instance it is shown, more particularly in Fig. 4, to consist of a coiled spring having, at its ends, caps *h'* and *i'* provided with loops *h''* and *i''* extending into the convolutions of the spring for the attachment thereto of the connecting members *g* and *g'*. The connecting member *g* is attached to a fastening element *j* secured to the belt *a* at the opposite end to the guide element *d* and this connecting member extends from the fastening element *j* through the guide element *d* and tension regulator *h* to the loop *i''* with which it slidably engages and is then returned through the tension regulator and guide element *d'* to a second fastening element *j'* aligned with the fastening element *j* transversely to the length of the belt. The connecting member *g'* is similarly held by the fastening elements *j''* and *j³* and passes through the guide elements *d''* and *d³* and the tension regulator *h* and around the loop *h''*.

The above described construction is employed for comparatively wide belts, but for those of a narrow nature as shown in Fig. 9 the connecting members *g* and *g'* may be attached to the fastening elements *j* and *j³* and after passing through the guide elements *d* and *d³* may be connected to the ends of the

tension regulator h without being returned through the guide elements d' and d'' to the fastening elements j' and j'' as shown in Fig. 4. As shown in Fig. 4, the connecting members g and g' as the belt contracts will slidably move through the guide elements d , d' , d'' and d'' and contract the tension regulator h , so that its full expansive force can be utilized to restore the connecting members to their initial position when the belt is relieved of its increase of tension. The extension of the tension regulator is limited by the guide elements d' and d'' contacting its ends, and its contraction is limited by its convolutions contacting one another. As the belt contracts the connecting members move through the guide elements in the direction indicated by arrows in Fig. 4 to allow of the separation of the places of attachment, and as the belt expands they move in the reverse direction to bring the places of attachment nearer each other. The ends of the connecting members are held by the fastening elements j , j' , j'' and j'' which may be said to constitute one of the places of attachment to the belt and the connecting members slidably move through the guide elements d , d' , d'' and d'' which may be said to constitute the other place of attachment.

In Figs. 1, 2, 2* and 5 the fastening elements and the guide elements consist of staples or loops secured to the outer surface of the belt, and in Fig. 4 the fastening elements at one end of the belt are shown to consist of eyes j'' through which the connecting members are laced.

In Fig. 2* the tension regulating means is shown attached to a section of a continuous belt, i.e., a belt in which the ends are united, and to provide for the extension and contraction of a belt of this character the tension regulating means is so arranged as to draw the points of attachment together to form a loop z which projects beyond the outer surface of the belt.

In Figs. 2, 4 and 6, the ends of the connecting members g and g' are extended through the apertures r' in the fastening elements j , j' , j'' and j'' and then looped as at p around the ends of the binders q to be returned through the apertures r in the binders q and the apertures r' in the fastening elements the ends of the binders having a notch q'' therein to prevent the displacement of the loops p therefrom. By drawing the connecting members through the fastening elements and through the apertures r , the length of the connecting members can be reduced and by "letting out" the connecting members their length can be increased. By keeping the loops p tight around the ends of the binders, a secure lock will be provided to hold the connecting members in their adjusted position as the tension upon the connecting members will draw the binders toward, and cause them to clamp the

connecting members against the fastening elements.

In Figs. 3, 6 and 9 the fastening element j is shown to consist of a bar having a channel therethrough for the connecting member and the bar shown in these figures is provided with a metal wear plate r^* having an aperture alined with and corresponding to the aperture r through the bar.

In Figs. 1, 2 and 5 the intermediate connecting members as they pass from the guide elements d' and d'' to the fastening element j and j'' are arranged obliquely to the length of the belt so that they will not cut into the rim of the pulley or wheels over which the belt revolves and the connecting members as they pass from the fastening element j and j'' to the guide elements d and d' may also be arranged obliquely to the length of the belt as shown in Fig. 10.

It is possible to vary the construction as above described, within the scope of the appended claims without departing from the nature of the invention.

Having thus fully described my invention what I claim as new and desire to secure by Letters Patent is,

1. A tension regulating means comprising a belt, a tension regulator means connected with the tension regulator and connecting one part of the belt to another part, means for attaching the connecting means at one place to the belt, and other means for slidably attaching the connecting means at another place disposed with regard to the first mentioned place lengthwise of the belt, and located between the tension regulator and the first mentioned means of attachment.

2. A tension regulating means comprising a belt, a tension regulator means connected with the tension regulator and connecting one part of the belt to another part, said connecting means being attached at one place to the belt, and slidably attached to the belt at another place disposed with regard to the first mentioned place lengthwise of the belt, said last mentioned place being intermediate the tension regulator and the first mentioned place of attachment.

3. A tension regulating means comprising a belt, a tension regulator means connected with the tension regulator and connecting one part of the belt to another part, means for attaching the connecting means at one place to the belt and arranged to adjust the length of the connecting means, other means for slidably attaching the connecting means to the belt at another place disposed with regard to the first mentioned place lengthwise of the belt, said last mentioned means being located between the tension regulator and the first mentioned means of attachment.

4. A tension regulating means comprising a belt, an extensible and contractile member, means connected with the extensible and con-

- tractile member and connecting one part of the belt to another part, means for attaching the connecting means at one place to the belt, other means for slidably attaching the connecting means to the belt at another place disposed with regard to the first mentioned place lengthwise of the belt, said last mentioned means being located between the extensile and contractile member and the first mentioned means of attachment, and means for adjusting the connecting means.
5. A tension regulating means comprising a belt, a tension regulator, means connected with the tension regulator and connecting one part of the belt to another part, means for attaching the connecting means at one place to the belt, and other means for slidably attaching the connecting means to the belt at another place disposed with regard to the first mentioned place lengthwise of the belt, and located between the tension regulator and the first mentioned means of attachment, and means for limiting the extending movements of the tension regulator.
- 15 6. A tension regulating means comprising a belt, a tension regulator, means connected with the tension regulator and connecting one part of said belt to another part, means for attaching the connecting means at one place to the belt and arranged to adjust the length of the connecting means, other means for slidably attaching the connecting means to the belt at another place disposed with regard to the first mentioned place lengthwise of the belt, said last mentioned means being located between the tension regulator and the first mentioned means of attachment, and means for limiting the extending movements of the tension regulator.
- 25 7. A tension regulating means comprising a belt, a tension regulator disposed transversely to the length of the belt and interme-
- diate its side edges, connecting means connected with the tension regulator, fastening means for adjustably attaching the connecting means at one place to the belt, and other means for slidably attaching the connecting means to the belt, said last mentioned means of attachment being located intermediate the tension regulator and first mentioned means of attachment.
- 35 8. A tension regulating means comprising a belt, a tension regulator disposed transversely to the length of the belt, connecting means connected with the ends of the tension regulator, fastening means for attaching the connecting means at one place to the belt and other means for slidably attaching the connecting means to the belt intermediate the tension regulator and the first mentioned means of attachment, said last mentioned means of attachment being arranged to limit the extending movement of the tension regulator.
- 45 9. A tension regulating means comprising a belt, a tension regulator disposed transversely to the length of the belt, connecting means connected with the ends of the tension regulator, fastening means for attaching the connecting means at one place to the belt and other means for slidably attaching the connecting means to the belt intermediate the tension regulator and the first mentioned means of attachment, said last mentioned means of attachment being arranged to limit the extending movement of the tension regulator, and means for adjusting the length of the connecting means.
